UNITED STATES PATENT OFFICE.

JOSEPH BECKER, OF WASHINGTON, DISTRICT OF COLUMBIA, ASSIGNOR TO EASTMAN KODAK COMPANY, OF ROCHESTER, NEW YORK, A CORPORATION OF NEW YORK.

COPYING AND ENLARGING CAMERA.

1,339,090.

Specification of Letters Patent.

Patented May 4, 1920.

Application filed January 18, 1917. Serial No. 143,085.

To all whom it may concern:

Be it known that I, JOSEPH BECKER, a citizen of the United States, residing at Washington, in the District of Columbia, have invented certain new and useful Improvements in Copying and Enlarging Cameras, of which the following is a specification.

The present patent application is identified, for convenience of reference in my related applications, as Case At.

The present specification hereinafter makes specific references to my related applications or patents, as follows: Case A, now Patent 1,178,474; Case K, now Patent 1,103,342; Case O, now Patent 1,103,343; Case T, now Patent 1,142,295; Case U, now Patent 1,190,214; Case Y, Serial No. 732,488, filed November 20, 1912, now continued as Case Au; Case Ab, now Patent 1,178,477; Case Ae, Serial No. 66,371, filed December 11, 1915; Case Af, now Patent 1,178,478; the above mentioned Case Au or continuation of Y, now Patent 1,289,088.

The invention consists in an entirely novel type of focuser which is specially adapted for use with copying or enlarging cameras and to which I have already referred (in describing Figures 10 to 15 of my said Case Ae), as a "single sight optical focuser" to distinguish it from the normal or "double sight optical focuser," typified, for instance, in Fig. 3 of my said Case A.

A "single sight" focuser can only be used in a copying or enlarging camera, but it differs radically from the mechanical focusers of my said cases K, O, T, U, and Y or Au, in that it does not automatically focus the camera, for it on the contrary leaves the three camera frames O, L, I entirely free; but it does automatically point out or indicate, at all times the exact focal condition of the camera. It constantly indicates whether the camera is in focus or out of focus; and, in case the camera is out of focus, it shows the direction in which it is out of focus, so that the camera can always be focused very easily by simply shifting the camera frames so as to bring the focuser into an in-focus-indicating position.

Incidentally, my invention consists in an

optical focuser of the radial cam type in which the basic or sector angle delta (Δ) is variable, and adjustable, as in my said Case Y, but the adjustment here serves to permit of setting the basic angle at any value that may, under present conditions, be necessary to suit any one of different lenses. Different lenses, under present conditions, require different basic or sector angles delta (Δ), in the focuser, in all cases where the substitution of one lens for another, on the lens frame L of the camera, changes the horizontally measured distance of the outer focal plane F' of the lens from the said lens frame L.

The accompanying drawing shows a form of the invention in which the focuser is mounted on top of the camera, because this form is most easily described and understood. In current practice, the focuser should preferably be mounted on the side of the camera as in Fig. 18 of my said Case A, because this arrangement is not only more compact, but generally more convenient.

Fig. 1 is the vertical meridional section of a copying or enlarging camera, comprising a very simple but fully operative form of my invention, having all adjustments needed to permit of adjusting and regulating the focuser so that it will operate in exact "3-and-all-point" correspondence with any one of different lenses; but, shown as being properly adjusted and regulated for the given lens 9 seen in the figure; and showing the focuser, moreover, in one of its focus-indicating positions; that in which the diametral object-to-image ratio is 2 to 5.

Fig. 2 is a diagram of the four essential material elements of Fig. 1, to wit sector delta (Δ), lens 9, screen 4, and screen 1, all placed and spaced as in Fig. 1, but with the additional imaginary dots and lines that are needed in giving a full explanation of the exact geometrical principles involved.

Fig. 3 is the scale for line dimensions in Figs. 1 and 2.

Fig. 4 is a table of all the fundamental angle and line dimensions occurring in Figs. 1 and 2.

Fig. 5 is a view, similar to that of Fig. 1, but illustrating the final phase of "adjustment number one," which is made on left infinity, for automatically determining that 5 special value of the sector angle delta (Δ) which is required to secure correct operation of the focuser with the particular lens 9 used.

Fig. 6 is the scale for line dimensions in 10 Fig. 5.

Fig. 7 is another view similar to that of Fig. 1, but illustrating the final phase of "adjustment number two," which is made on right-hand infinity, for determining the 15 offset u of pin T and the inclination epsilon third (ϵ''') of arm 40 or that properly inclined and horizontally translated relative position of groove 42 on frame O, which determines the rectilinear locus 42 of pin 20 tile V on frame O, for all lenses differing in focal length, but having the same identical external principal focal plane F'Z'.

Fig. 8 is a third view similar to that of Fig. 1, but illustrating that particular phase 25 of "adjustment number three" which immediately precedes the last step, or insertion of pintle V, and which determines the exact position v that must be occupied by said pintle V as predetermined by the focal, or 30 f length, value of the particular lens used.

Fig. 9 is the scale for line dimensions used in Figs. 7 and 8.

Verification by scale and by computation is facilitated by the selection of whole number values for all linear elements, and such 35 selection was facilitated by making the basic angle epsilon prime (ϵ') of such value that its cosine is exactly equal to minus three-fourths, as indicated in said table, 40 Fig. 4.

The value of the angle epsilon prime (ϵ') itself is given in the table, Fig. 4, in two 45 different forms. It is first expressed in degrees, minutes, seconds, and tenths of seconds as $138^\circ 35' 25.4''$; and it is again expressed, more simply and more clearly in decimal form, as 1.5399 Q, which is its value in quadrants or right angles.

The quadrant or right angle is the angular 50 unit already used in my said Case Y, now Au and in my said Case Ae.

The accuracy of the drawing hardly warrants the use of more than three decimal places in the quadrant value, 1.5399 Q; but 55 the numerical values are, nevertheless, given as fully as they are, merely to emphasize the fact that the basic angle is as arbitrary in value as may automatically be predetermined by the optical dimensions of the particular lens used.

My copying or enlarging camera comprises a table 10 with two rails, such as 11, to form, on top of table 10, a suitable guide way for a camera OL. This camera OL 65 is separately usable as a view or tripod

camera, and to this end it has its base 12 provided with a threaded aperture 3 which is adapted to receive the tripod screw 64, as seen in Fig. 7.

A vertical screen I, rigidly mounted at the 70 extreme right hand end of the table 10, constitutes the third or image frame of the combination.

The lens frame L is provided with a vertical extension or post 13 which supports 75 the pivot D of a sector 14. This post 13 also supports a small bracket 5, through which is threaded a screw 6 which is adapted to engage and press against the narrow cylindrical edge of sector 14 to lock the 80 sector against rotation as desired whenever the focuser is being regulated and adjusted, as explained later on, for use with a given lens.

Sector 14 has a rigid radial arm 16 with a 85 radial cam slot 17 adapted to have sliding engagement with the object frame pintle V; and it has an angularly adjustable arm 16', whose inclination delta (Δ) to arm 16, may be fixed at any desired value by means of a 90 clamp screw 18 which engages a nut that travels in an undercut arcuate groove 19.

The arm 16' has a pin S which serves as a bead sight in combination with the slightly projecting end of pivot D acting as a peep 95 sight, and the radial line of sight 17' thus determined, constitutes the "single sight" of the combination.

The object frame O is grooved at 30 to form a slideway for a metallic fixture 31, 32, 100 33, whose horizontal web 31 is slotted and traversed by a screw 34 which serves to clamp the fixture in any desired longitudinal adjustment on the said object frame O.

The fixture 31-33 carries a stud T on 105 which is pivotally mounted the arm 40, and this arm 40 has a clamp screw 41 which passes through arm 40, into a nut that has sliding engagement in an arcuate undercut groove 36 formed in wall 33 of the fixture, 110 so that arm 40 may be firmly clamped and rigidly held at any desired inclination, which, for present purposes, is best measured by the obtuse angle epsilon-third (ϵ''').

The arm 40 is provided with a straight 115 radial undercut groove 42 which also admits a nut into which engages the cylindrically reduced and threaded end of the object frame terminal or pintle V. Terminal V may accordingly be clamped to arm 40 at 120 any desired radial distance TV from pivot T, and in this way the distance ZD of its zero position Z from point D may be made of any value imposed by the focal length f of the particular lens to be used.

The fixture 31-33 has its rear vertical wall 32 perforated at 37 to form a peep, but stud T really serves as a peep sight proper when the device is used as a "double-sight focuser". Coöoperating with 37, as bead 125 130

sight, is a pin or stud U which is fixed in upright 13 at the same level as T and 37.

When the device has been properly adjusted and regulated, and the focuser arm 5 DS points at V', as in Fig. 1, all of the equations given in the table, Fig. 4, are satisfied.

Before proceeding to adjust and regulate the device for use with any given lens, we 10 must first locate and permanently mark point V' on the image frame I in direct horizontal alinement with sights 37 and U.

When point V' has once been located, there is no further use for the horizontal 15 sight line TU, except when the camera part OL is removed for use on a tripod as in Fig. 7, for then V' is no longer present except as some unknown point in the object to be photographed, and this unknown point 20 must be discovered by sighting along TU, substantially as explained in my said Cases A and Ae in connection with the "double sight focusers" there disclosed.

V' being therefore determined and distinctly marked on the image plane P'V', we 25 may adjust and regulate the focuser for use with any one of different lenses, substantially as first explained at length in my said Case K, by means of three independent 30 focusing operations.

The lens to be used is mounted on frame L in any preferred manner. This fixes the position of the outer focal point F' as well as the position of the imaginary lens frame 35 point Z', which represents the zero position of the image frame terminal V'.

Moreover, as D is also a lens frame point, the basic angle epsilon prime (ϵ') is also seen to be predetermined by the simple 40 operation of mounting the lens 9.

Now, the sector angle VDS or delta (Δ) must be made equal to the basic angle epsilon prime (ϵ') and this first structural adjustment is determined by focusing on, 45 as in Fig. 5, left infinity.

The angle VTE or epsilon third (ϵ''') must also be made equal to epsilon prime (ϵ'), and this is done by focusing on right infinity, as illustrated in Fig. 7.

Finally, the radial distance TV, or rather Z'D minus DZ, must be determined by focusing the end frame O on the end frame I at any preferred finite distance, as illustrated in Fig. 8.

55 A detailed description of these three separate adjustments will now be given.

Adjustment No. 1, on left hand infinity.

Remove pintle V to free the sector 14 and 60 then set the sector 14 so that its radial arm 16 shall point as in Fig. 6 to left infinity and temporarily fix it, in such position, by means of the clamp screw 6.

Remove the object plane, screen, or negative 65 4, to admit parallel rays 21, 22, 23 from

left infinity, directly through the object frame O, to the lens, and shift the lens frame L to the right until a test object at left infinity has been sharp-focused at P', on the image frame I. This evidently reduces 70 the Newtonian spaces F'P' and Z'V' to zero value, and it makes Z' temporarily identical with V'. To preserve this identity, temporarily clamp the camera bed 12 to table 10.

Now loosen screw 18 to free arm DS or 75 16', and turn this arm until it points directly at V', and finally clamp it to sector 14 in such position by tightening screw 18. This has made the sector angle (Δ) exactly equal to the basic angle epsilon prime (ϵ') 80 and completes the first adjustment.

Screw 6 may therefore be turned down to free the sector 14 and prepare for adjustment No. 2, which involves focusing on right hand infinity. 85

Adjustment No. 2, on right hand infinity.

This is most easily performed on a tripod. Hence, first mount the camera OL, as in Fig. 7, on a tripod 60 to 64 and sighting along TU, pick out an object point at right-hand infinity, as test object, and as a substitute for the present mark V'. The ray from such object point at infinity to the eye at E is indicated by arrow 51. Other parallel rays 90 from the same object point are indicated by arrows 52, 53, 54, 55.

Now turn disk 14 until the sight line DS points on the same said object. This sets DS parallel to TU; and to hold it firmly 100 in this position, the screw 6 is again screwed up against sector 14, as indicated in Fig. 7.

A focusing screen 4 is now inserted in the object frame O, to be set in focus on the same infinitely distant test object, or on the parallel rays 53, 54, 55; and as this practically reduces PF to zero value, as shown in Fig. 7, the object frame is temporarily clamped to base 12 in its thus determined zero position. 105

The two clamp screws, 34 and 41 are now loosened so that arm 40 may be freely brought up into the position of Fig. 7, where it registers exactly in position and inclination with radial arm 16, so that its inclination epsilon third (ϵ''') is exactly equal and opposite to the inclination epsilon prime (ϵ') of the base line Z'D'. It is therefore permanently clamped in its thus determined proper relative position to the object frame 110 O by firmly tightening the two screws 34 and 41.

Clamp screw 6 is now loosened to free the sector 14 and prepare for adjustment No. 3. 115

Adjustment No. 3, at a finite distance.

The camera bed 12 is temporarily clamped to the table 10 in any preferred position, such as that seen in Fig. 1, and the object frame O is moved back from F to P through 120 130

a distance FP , which is equal to 12 centimeters in the case illustrated, to set it sharply in focus on the image frame I , and it is also temporarily clamped to its bed 12, 5 so that the three camera frames, to wit: object frame O , lens frame L , and image frame I , are all three positively held in proper focal relation. In such case the properly adjusted sight line DS should 10 point at V' . The sector 14 is therefore turned until DS does point exactly at V' , as shown in Fig. 8, and this proper inclination of the sight arm DS is fixed by bringing screw 6 a third time up against sector 14, 15 also as shown in Fig. 8.

The radial cam slot 17 now crosses the slot 42, in arm 40, at a certain point v which is the position that should be occupied by pintle V .

20 Pintle V is therefore inserted and firmly fixed to arm 40, in its thus determined permanent position.

Screw 6 is again loosened and this completes the third adjustment.

25 The combination is now ready for use either as a copying camera with "single sight" focuser or as a tripod camera with a "double sight" focuser, and the operation in either capacity is perfectly obvious.

30 The advantages of a "single sight" focuser over the mechanical focuser of my Case T, for instance, is that the three frames O , L , I , of the camera, may be moved in any manner and set in any desired relative position, as 35 freely as if no focuser were present; but the single sight line 17' will at all times indicate automatically to what extent and in what direction the camera may be out of focus; and how it may generally be brought into 40 focus in either preferred one of two different ways, to wit: by moving the camera OL as a whole along on table 10; or, secondly, by simply moving the object frame O alone.

45 *Theory of the correctly regulated focuser.*

The three adjustments described above, by their combined and properly ordained action have accomplished two positive things, to wit: first, they have fixed the 50 henceforth invariable value of the sector angle Δ ; secondly, they have fixed the henceforth invariable relative position which is occupied by pintle V , with relation to the object frame O .

55 It only remains to be proved that there has been established between the focuser, in its focus-indicating positions, and the lens 9, that exact "3-and-all point correspondence" which I first disclosed in connection with the 60 theoretically exact optical focusers seen in Figs. 1, 2 and 19 to 22 of my said Case A. (See particularly, in my said Case A, the conclusion on page 11, lines 20 to 24.)

The following proof, though long, has the 65 advantage of being entirely independent of

the mechanical principles disclosed in any of my said other Cases A, K, O, T, U, Y, Ab, Ae, Au, Ax.

Fig. 2 diagrammatically represents the properly adjusted and regulated camera of 70 Fig. 1, set to copy at the same diametrical object-to-image ratio $PW/P'V'$ of 2 to 5. The fulcrum of the bent lever 16, 16' is marked as two points D and D' , corresponding to the two points C and C' of the rectangular radial cams Figs. 12 to 20 of my said Case U; also to the two points A and A' in Figs. 4 and 17 of my said Case A.

Omitting W as a purely secondary optical point, Fig. 2, therefore, really shows sixteen 80 important and separately identified structural or geometrical points, which may be distinguished as: First, the three "object-frame" points P , V , T , which are relatively fixed, but together movable with the object-frame O , as fixed points of said object-frame; secondly, the eleven "lens-frame" points D , D' , K , K' , N , N' , F , F' , Z , Z' , Z'' , which are all relatively fixed, but all movable together with the lens frame A , as fixed 85 points of the said lens frame; thirdly, the two image frame points P' , V' , which are relatively fixed, but both movable together with the image frame I , as fixed points of said image frame.

90 In the present, or Fig. 1, embodiment of my invention, the image frame I is normally stationary, and the other two frames L and O are movable.

95 It is easier, however, as in my said prior Cases K, O, T, U, to conceive all displacements as they would be in those forms of the invention which have the lens frame L stationary.

Assuming, therefore, in Fig. 2, that the 105 lens frame L is, and always remains, stationary, the eleven lens frame points D , D' , K , K' , N , N' , F , F' , Z , Z' , Z'' , will all be stationary; and, the five end-frame points P , V , T , P' , V' , will alone be movable.

110 This distinction is graphically made clear in Fig. 2, by representing the five movable end-frame points, P , V , T , P' , V' , as perforated or wheeled dots, to indicate motion; whereas, the eleven lens frame dots are all 115 shown as unperforated or black dots, to indicate fixedness.

120 The double point D , D' , and the projection K' of D' on the horizontal line of sight are structurally predetermined, and absolutely invariable, for any lens that may be used in the camera.

125 After a given lens 9 has been mounted as explained above, its four cardinal points, F , N , N' , F' , are likewise fixed, and it is noted that in the present case the distance z of the nodal point N from the vertical plane $D'K'$ is 1.5 centimeters. This offset z may have any plus or minus value, and it may even accidentally be *nil*; but as indicated in the fig-

ure, its value is quite arbitrary, except in so far as such value is automatically predetermined, as in the present case, by the optical dimensions of the particular lens used.

5 The vertical plane through the outer principal focal point F' meets the horizontal sight line TV' in Z' . Hence the mere act of mounting the lens 9 has predetermined, first, the location of point Z' ; secondly, the length 10 of the base line $Z'D'$; thirdly, the inclination epsilon prime (ϵ') of the base line $Z'D'$.

It has likewise determined the location of point Z'' , which is the zero position of pin T , for the distance of Z'' from K' must 15 equal the distance of Z' from K' . It has furthermore determined the location of Z , or zero position of V , because point Z must be on DZ'' , and the product of $Z'D' \cdot DZ$ must equal the square of the focal length of 20 the lens. The inclination of $Z'D'$ is most conveniently measured by the obtuse angle epsilon prime (ϵ'), because the sector angle delta (Δ) must equal epsilon prime (ϵ'), hence the value of the sector angle delta 25 (Δ) is likewise predetermined, and all elements of the focuser, that is to say all of its adjustable dimensions both linear and angular are predetermined by the simple act of mounting any given lens on the lens 30 frame L .

All necessary and sufficient structural conditions are summed up in the tabular equations that are noted in Fig. 4, and they have all been satisfied by the adjustments 35 described above.

By focusing on left infinity, as in Fig. 5, the sector angle delta (Δ) was made equal to the basic angle epsilon prime (ϵ').

By focusing on right-hand infinity, as in 40 Fig. 7, the angle epsilon third (ϵ''') was made equal to the sector angle delta (Δ); and, as the delta (Δ) had previously been made equal to the basic angle epsilon prime (ϵ'), the groove 42 has exactly been set anti- 45 parallel to the base line $Z'D'$. Angles epsilon second (ϵ'') and epsilon (ϵ) of Fig. 2, being necessarily equal to angle epsilon third (ϵ'''), are likewise fixed by the same operation. After completion of the adjustment 50 seen in Fig. 7 therefore the equality of the five different representations of the basic focuser angle is insured, or, in symbols,

$$\epsilon = \epsilon'' = \epsilon''' = \Delta = \epsilon'$$

55 By focusing at a finite distance as in Fig. 8, the spaces PF and $F'P'$ were set to satisfy Newton's formula (equation 1 of my said Case A, or equation 4 of my said Case K), and then by bringing $D'S$ into alignment with V' , the position v of pintle V was located, and V could be fixed in its proper relative position with relation to the object frame O .

In the diagram Fig. 2, the base line $Z'D'$ 60 and the anti-base line DZ are anti-parallel

with reference to the horizontal $h\ h'$, and it is convenient to conceive of these two lines as representing the two knife edge forming faces of a wedge that serves as a ful ZDZ'K'K, for the bent lever 16, 16'.

70

The bent lever 16, 16' in any given position determines two triangles ZVD and $Z'D'V'$, which vary in shape and size, but which are always similar because their corresponding angles always remain equal, 75 that is to say

$$\epsilon = \epsilon' \quad (1)$$

$$\varphi = \varphi' \quad (2)$$

$$\omega = \omega' \quad (3)$$

80

The angle epsilon (ϵ) at Z and the angle epsilon prime (ϵ') at Z' are equal as the result of adjustments 1 and 2, and they are invariable because they remain equal to the sector angle delta (Δ).

85

The other two corresponding angles of these triangles are variable; but they remain respectively equal, as need only be proved for one of them, the angle omega, omega prime (ω, ω'), for instance.

90

Angle omega (ω) equals angle omega second (ω'') because these two angles were simultaneously generated by equal clockwise rotations of the rigidly connected arms 16, 16', from the position occupied by these 95 arms 16, 16' in Fig. 7, where omega (ω) and omega second (ω'') are both *nil*.

On the other hand angle omega prime (ω') and angle omega second (ω'') are equal as having one side $D'V'$ in common and the 100 other two sides $D'Z', V'Z'$, parallel.

These conclusions in symbols become

$$\omega = \omega''$$

$$\omega' = \omega''$$

105

Whence by division

$$\omega/\omega' = \omega''/\omega'' = 1$$

and by multiplication

$$\omega = \omega'$$

110

The third angle phi, phi prime (φ, φ') of the two triangles ZVD , $Z'D'V'$ could, if necessary be proved equal in similar manner; or, more simply, by noting that two 115 triangles which have two angles equal must have the third angle equal to make up the sum of two right angles.

The triangles ZVD , $Z'D'V'$ having their corresponding angles equal in all positions 120 of the bent lever 16, 16' must always have their homologous sides proportional, so that the following equation

$$\frac{VZ}{DZ} = \frac{Z'D'}{Z'V'} \quad (4)$$

125

is always true for all inclinations of the bent lever 16, 16'.

In this proportion, or equation 4, the two 130

means DZ , $Z'D'$ are invariable; and the two extremes VZ , $Z'V'$ are variable; moreover, the product $VZ.Z'V'$ of the extremes is always equal to the product $DZ.Z'D'$ of the means. But the last product is $f.f$ or f^2 because the distance DZ has indirectly been fixed by "adjustment number three" of Fig. 8, where, after insertion of pin V , the product $VZ.Z'V'$ is identical with $PF.F'P'$, and hence evidently equal to f^2 .

In Fig. 1, therefore, which is simply Fig. 8 with pintle V inserted,

$$Z'D'.DZ = VZ.Z'V' = PF.F'P' = f^2 \quad (5)$$

15 This equation 5 holds, however, not only for the position of Fig. 1 but for all other positions, for the following reasons:

Any displacement imparted to P is necessarily imparted to V so that in all positions 20 of the object frame O

$$PF = VZ \quad (6)$$

On the other hand, any change made in the distance $F'P'$ is equally and simultaneously made in the distance $Z'V'$, hence for 25 all values of $F'P'$.

$$F'P' = Z'V' \quad (7)$$

In all focus-indicating positions, equations 30 5, 6, and 7, therefore yield

$$PF.F'P' = VZ.Z'V' = DZ.D'Z' = f^2 \quad (8)$$

That is to say Newton's formula, satisfied in one position, is necessarily satisfied in all.

35 The simplest rule for plotting the focuser, where all lens dimensions are known, is: first, plot the outer principal focal plane F' of the lens to locate Z' ; secondly plot $Z''K'$ equal to $K'Z'$; thirdly on DZ'' plot Z by 40 making DZ equal to the quotient of $D'Z'$ into f^2 ; fourthly, draw PV equal and parallel to FZ to locate V on the object frame O ; fifthly, make sector angle delta (Δ) equal to the basic angle $D'Z'V'$ or epsilon 45 prime (ϵ').

This rule makes no reference whatever to arm 40 or groove 42, which are therefore seen to be of no importance, except during the process of adjustment and regulation, to 50 permit of securing correct adjustment and regulation without knowing the focal length or any other optical dimension of the particular lens used.

The fundamental principle involved in

the present invention is that the bent lever 55 16, 16', in Fig. 2, always determines spaces $VZ.Z'V'$ whose product $VZ.Z'V'$ for any given position of the lever, is equal to the invariable product $DZ.Z'D'$ of the anti-parallel base lines; such contact product 60 $DZ.Z'D'$ being itself made equal to f^2 .

The two base lines DZ , $D'Z'$ evidently correspond to the lines AG and AH in Fig. 1 of my said Case A, and to the line CD , $C'D'$ of Fig. 19 in my said Case U, where 65 the angle $DC D'$, corresponding to the present angle $ZD Z'$, is *nil*.

General remarks.

NOTE 1.—My first disclosure of a radial 70 cam focuser with adjustable basic angle delta (Δ) was made in my said Case Y.

NOTE 2.—The three adjustments, herein 75 fully described because of the peculiar features involved, are really the same in substance and principle as those already used in my said cases K, O, T, U, Y Ab, Ae, and Af.

NOTE 3.—When either end frame, O or I , is called the "object frame", the other end 80 frame, I or O , must be considered on the "image frame". Thus frame O serves as "image frame" of the tripod camera OL , but as "object frame" of the enlarger, Fig. 1.

85 What I claim as my invention and desire to secure by Letters Patent is:

The combination with a photographic camera having a focuser of the radial cam type comprising: first, a radial arm pivoted 90 on the lens frame of the camera and adapted to engage the plate or film-holding frame of the camera; secondly, a radial element for the object likewise pivoted on the said lens frame of the camera; thirdly, means 95 connecting said first two radial elements so that they shall rotate in constant angular relation; such connecting means comprising a normally rigid unit composed of parts whose relative position can be varied 100 to adjust the angular dimension of such unit and thereby set the said constant angular relation or basic angle of the focuser at any desired value.

In testimony whereof, I have signed my 105 name to this specification.

JOSEPH BECKER.
